UNITED STATES PATENT OFFICE

139,574

DESIGN FOR A PULL TOY

Howard William Beaver, Eagle Rock, Calif.

Application June 2, 1944, Serial No. 113,842

Term of patent 7 years

(Cl. D34—15)

To all whom it may concern:

Be it known that I, Howard William Beaver, a citizen of the United States, residing at Eagle Rock, in the county of Los Angeles and State of California, have invented a new, original, and ornamental Design for a Pull Toy, of which the following is a specification, reference being had to the accompanying drawing, forming part thereof, in which Figure 1 is a side elevational view of a pull toy showing my new design, the opposite side presenting substantially the same appearance as the side shown, and Figure 2 is a top plan view of the same.

I claim:

The ornamental design for a pull toy, substantially as shown and described.

HOWARD WILLIAM BEAVER.
